Primary Examiner — Abraham Bahta(74) *Attorney, Agent, or Firm* — McDonald Hopkins LLC(57) **CLAIM**

The ornamental design for a label sheet, as shown and described.

DESCRIPTION

FIG. 1 is a front view of a first embodiment of a label sheet showing our new design;

FIG. 2 is a left side view of FIG. 1 thereof;

FIG. 3 is a right side view of FIG. 1 thereof;

FIG. 4 is a top view of FIG. 1 thereof;

FIG. 5 is a bottom view of FIG. 1 thereof;

FIG. 6 is a back view of FIG. 1 thereof;

FIG. 7 is a front view of a second embodiment of a label sheet showing our new design;

FIG. 8 is a left side view of FIG. 7 thereof;

FIG. 9 is a right side view of FIG. 7 thereof;

FIG. 10 is a top view of FIG. 7 thereof;

FIG. 11 is a bottom view of FIG. 7 thereof; and,

FIG. 12 is a back view of FIG. 7 thereof.

The broken lines in the figures are included for the purpose of illustrating portions of a label sheet assembly and form no part of the claimed design.
